UNITED STATES PATENT OFFICE

158,072

BRIDAL DRESS HANGER

Frances M. Herwitz, Brookline, Mass.

Application July 12, 1947, Serial No. 140,254

Term of patent 3½ years

(Cl. D33—8)

To all whom it may concern:

Be it known that I, Frances M. Herwitz, a citizen of the United States, residing at Brookline, Massachusetts, have invented a new, original, and ornamental Design for a Bridal Dress Hanger, of which the following is a specification, reference being had to the accompanying drawing, forming a part thereof.

I claim:

The ornamental design for a bridal dress hanger, as shown.

FRANCES M. HERWITZ.
